DOOR LOCK

Gabriel Madland, Chicago, Ill., and Richard A. Lehnhoff, Hammond, Ind., assignors to The Youngstown Steel Door Company, Cleveland, Ohio, a corporation of Ohio

Application September 13, 1939, Serial No. 294,658

5 Claims. (Cl. 292—284)

This invention relates to door locks and is directed more particularly to locks for sliding doors of railway house cars capable of preventing lashing of the doors when locked.

It is an object of this invention to provide locks of the character set forth which shall be sturdier in construction and more effective in operation than similar locks heretofore used.

A further object is the provision of such locks wherein bending and distortion of the locking pins shall be obviated.

A further object is the provision of locks which shall embody locking pins and pin supports, the latter carrying means for insuring alinement between seal receiving slots formed in the pins and pin supports.

A further object is to provide locks embodying supports for locking elements which supports shall be more firmly united with the doors upon which they are mounted and which shall be so associated with relatively sturdy reinforcing members on said doors as to further said union.

Other objects of the invention will become clear as the description thereof proceeds.

In the drawings forming part of this specification:

Figure 1 is a fragmentary elevation illustrating a lock embodying the instant invention.

Figure 2 is a horizontal section taken on line 2—2 of Figure 1.

Figure 3 is a vertical section taken on line 3—3 of Figure 1.

In the drawing the lock embodying the instant invention is illustrated as applied to the double doors of a railway house car. The lock is applicable as well with some modification in the structure of the lock bracket, which is well known, to railway house cars utilizing single doors. As illustrated, the lock embodies a locking bracket 10 secured by means of rivets 11 to a horizontal corrugation 12 with which the door panel 13 of the auxiliary door 14 may be provided. Additionally the lock is secured by means of rivets 15 to a vertical corrugation 16 which may be formed in the metallic panel 13.

The lock bracket 10 which is preferably a casting embodies spaced housings 17 and 18 adapted to slidably receive a locking pin 19. As clearly illustrated in Figure 1 of the drawing, the opposed faces 20 and 21 of the housing members 17 and 18 diverge outwardly for a purpose which will hereinafter appear.

The lock bracket is provided with a vertical flange 22 formed with a seal receiving slot 23. Additionally the lock bracket is formed with a

projection 24 adapted to cooperate with the locking pin 19 for the purpose hereinafter disclosed.

The locking pin 19 as shown in Figure 1 of the drawing is tapered. The straight side 25 of the said pin is adapted to bear against the adjacent sides of the housing members 17 and 18. The opposed side of the pin is inclined downwardly as indicated at 26. This side of the pin, moreover, is inclined obtusely relative to the rear face of the pin as indicated at 27. The pin is provided with a seal receiving slot 28 which is aligned with the seal receiving slot 23 on the lock bracket 10 when the pin is in its operative position.

A tell-tale in the form of a lug 29 is formed on the lock bracket which additionally is provided with a padlock receiving opening 30 formed in the reinforcing rib 31.

The lock embodies also a hasp fastener 32 secured by means of rivets 33 upon a horizontal corrugation 34 which may be formed in the metallic panel 35 of the main door 36 of a double door construction. The hasp fastener 32 is formed with a gooseneck 37, the free end 38 of which projects through a vertical corrugation 39 which may be formed in the panel adjacent to the vertical margin thereof and through a hasp fastener reinforcement 40 secured to the inside of the horizontal corrugation 34 by means of the rivets 33. This end of the neck of the hasp fastener is rigidly secured as by means of welding 41 to the hasp fastener reinforcement. The portion of the hasp fastener reinforcement through which the neck of the hasp fastener extends is disposed within the vertical corrugation 39 so as to abut to the outermost wall of the corrugation.

The metallic panel 35 is provided with a plane marginal portion 42 reinforced by means of a substantially channel shaped member 43, the leg 44 of which is spaced from the outer wall of the vertical corrugation 39. Within this space a metallic filler 45 is disposed and fastened as by means of welding to the leg 44 and the outer wall of the vertical corrugation 39 so as to constitute a backing member for the hasp fastener reinforcement 40.

A hasp or locking member 46 is swingably carried by the hasp fastener. The hasp is formed with an aperture 47 defined by the front and rear walls 48 and 49 and by the side walls 50 and 51. The side wall 50 is inclined similarly to the inclined side 26 of the locking pin. The hasp or locking member 46 is provided with an elongated opening 52 beyond the aperture 47 and is adapted to receive the lug 29 so as to indicate that the pin will be properly disposed in its operative position.

tion to receive a seal. The hasp is also provided with an opening 53 adapted to be alined with the opening 30 in the operative position of the hasp for the purpose of receiving a padlock if desired.

To lock the doors 14 and 36 together the hasp 46 is disposed between the housing members 17 and 18 of the lock bracket 10. The pin 19 is then slidably received within the housing members 17 and 18 and extends through the aperture 47 formed in the hasp. The structure of the hasp is such that the pin is completely embraced by the walls of the hasp defining the aperture so as to obviate bending and distortion of the pin heretofore encountered. The inclined side 26 of the pin and the inclined wall 50 of the hasp are in engagement and the straight side 25 of the pin abuts the adjacent straight sides of the housing. In its operative position the projection 24 engages the rear face of the locking pin thereby insuring alinement between the seal receiving slots 23 and 28 and protection of the seal against shearing. It is clear that in the event the main and auxiliary doors are not in contact, movement of the main door in opening direction is precluded and movement of the main door in closing direction will cause automatic lowering of the pin under action of gravity so as to reestablish engagement between the pin, the wall 50 and the housing members 17 and 18.

Welding of the free end of the neck of the hasp fastener to the hasp fastener reinforcement prevents pulling out of this end. Moreover, possible shifting of the hasp and hasp fastener toward the adjacent end of the door 36 is obviated by the utilization of the filler 45 and the strength of the front edge reinforcement 43.

The outward divergence of the opposed faces of the housing members 17 and 18 precludes binding of the hasp between these walls upon relative vertical movement of the doors 14 and 36. In this manner bending of the hasp is avoided.

It will be apparent that numerous changes and modifications in the details of the invention will be clear to those skilled in the art. It is intended, therefore, that all such modifications and changes be comprehended within this invention, which is to be limited only by the scope of the claims appended hereto.

We claim:

1. A lock for sliding doors comprising a lock bracket adapted to be secured to a relatively stationary member, a tapered locking pin slidably mounted on said lock bracket, a locking member adapted to be mounted upon a door slidably associated with said relatively stationary member, said locking member including front, side and rear walls defining an aperture, one of said side walls and a side of said pin being similarly inclined, said pin extending through said aperture when said locking member and pin are operatively associated, the inclined side of said pin abutting said inclined side wall and the other side of said pin abutting said lock bracket, the inclined side of said pin and said inclined wall being obtuse to said rear wall, said pin being biased downwardly by the action of gravity for the purpose set forth.

2. A lock for sliding doors comprising a lock

bracket adapted to be secured to a relatively stationary member, a tapered locking pin slidably mounted on said lock bracket, a locking member adapted to be mounted upon a door slidably associated with said relatively stationary member, said locking member including connected front, side and rear walls defining an aperture, one of said side walls and a side of said pin being similarly inclined, said pin extending through said aperture when said locking member and pin are operatively associated and being completely embraced by said walls, the inclined side of said pin abutting said inclined side wall and the other side of said pin abutting said lock bracket, the inclined side of said pin and said inclined wall being obtuse to said rear wall, said pin being biased downwardly by the action of gravity for the purpose set forth.

3. In a railway car having a door embodying a metallic panel formed with a vertical corrugation adjacent to a vertical margin of said panel and provided with a marginal stiffener spaced from said corrugation, a hasp fastener having a goose-neck secured to the outside of said panel, a hasp fastener reinforcement secured to the inside of said panel, the free end of said neck extending through said panel and said hasp fastener reinforcement, said hasp fastener reinforcement abutting said corrugation, and means in alinement with said reinforcement disposed between and abutting said corrugation and said marginal stiffener for the purpose set forth.

4. In a railway car having a door embodying a metallic panel provided with an outwardly extending member adjacent to a vertical margin of said panel and a marginal stiffener spaced from said member, a hasp fastener, a hasp fastener reinforcement, means securing said hasp fastener and said hasp fastener reinforcement to said panel, a portion of said hasp fastener extending through said panel and said hasp fastener reinforcement, said hasp fastener reinforcement abutting said member, and means disposed between and abutting said stiffener and said member, said means backing up said hasp fastener reinforcement.

5. In a railway car having a door embodying a metallic panel provided with an outwardly extending member adjacent to a vertical margin of said panel and a marginal stiffener spaced from said member, a hasp fastener, a hasp fastener reinforcement, means securing said fastener and said reinforcement to said panel, said hasp fastener having a portion extending through said panel and said hasp fastener reinforcement, said reinforcement abutting said outwardly extending door member, means disposed between and abutting said marginal stiffener and said member and backing up said hasp fastener reinforcement, a hasp supported by said hasp fastener, and means mounted upon a portion of said car associated with said door adapted to engage said hasp to lock said door, said hasp exerting a pull on said hasp fastener, a portion of the pull being transmitted by said hasp fastener reinforcement and said second mentioned means to said marginal stiffener.
